UNITED STATES PATENT OFFICE.

COLEMAN MERIWETHER, OF LOUISVILLE, KENTUCKY, ASSIGNOR TO PETER C. REILLY,
OF INDIANAPOLIS, INDIANA.

APPARATUS FOR HANDLING CONCRETE PIPES.

Application filed March 28, 1921. Serial No. 456,298.

To all whom it may concern:

Be it known that I, COLEMAN MERIWETHER, a citizen of the United States, residing at Louisville, in the county of Jefferson and State of Kentucky, have invented a new and useful Apparatus for Handling Concrete Pipes, of which the following is a specification.

In handling concrete pipe sections, which frequently weigh many hundreds of pounds, and in turning them from vertical to horizontal position and vice versa, it is difficult to get a proper hold on the pipe sections for handling them.

It is the object of my present invention to provide a device for gripping such sections, which device will be applicable to sections of different diameters, and which will enable the sections to be handled easily and expeditiously.

My present invention is a development and improvement on that shown in Patent No. 933,093, granted to John C. Mitchell and myself on September 7, 1909. In such prior patent the gripping band was of invariable length and was suitable for only one size of pipe section.

According to my present invention, the gripping band is made of sections, which may be inserted or removed as desired to vary the length of the band.

The accompanying drawing illustrates my invention: Figs. 1 and 2 are side and front elevations respectively of an upright pipe section with my improved handling device in position thereon ready to lift it; Fig. 3 is a view showing the pipe section lifted and tilted; Fig. 4 is an enlarged fragmentary section through the pipe at one end of the gripping band, showing the construction of the band; Fig. 5 is an elevation of one end of the gripping band, showing the pulley-carrying end member and the beginning of the series of removable sections, interconnected by their pivot pins; and Fig. 6 is an elevation of one of the removable sections by itself.

The concrete pipe section 10, of any suitable construction, is universally molded in upright position, as shown in Figs. 1 and 2, and it is necessary to turn this into horizontal position when it is laid. This is difficult because of the size and weight of the section, as it may weigh many hundred pounds.

In order to handle this section, and tilt

it from upright to horizontal position, I provide a gripping band which passes somewhat more than half way around the circumference of the pipe section 10. This gripping band is composed of two end members 11, in the form of hooks between the two legs of each of which a pulley 12 is mounted, and a series of separate sections 13 which are hinged to one another and to the end sections 11 to form an articulated band. The hinge joints are provided by removable pivot pins 14 which pass through suitable mating ears 15 on the ends of the sections 10 and 13, the pins 14 being removable and being held in place by cotter pins 16. The number of sections 13 is made sufficient so that the entire gripping band extends slightly more than 180° around the pipe, as is indicated by having the end section 11 to the left of the axis in Fig. 1. The sections of the band will fit the outer surface of the pipe section 10 closely only for a given size, but the sections are relatively short and will fit sufficiently close for either larger or smaller pipes. A chain 17 hung by its ends on a cross bar 18 carried by a suitable crane (not shown) passes around the pulley 12 in the two end members 11, the ends of the chain between such pulleys and the cross bar 18 passing up from the pulleys, and the bight of the chain between the two pulleys passing around that part of the circumference of the pipe section 10 which the gripping band 11-13 does not encircle. Thus the bight of the chain 17 and the gripping band together completely encircle the pipe section, and as the cross bar 18 is lifted the gripping band and the bight of the chain are tightened on the pipe and firmly grip it. The center of gravity of the upright pipe section is slightly offset from the lifting line of the chain 17, as is indicated in Fig. 1, so that as the pipe is lifted it swings toward the position shown in Fig. 3. The amount by which it swings, and the force of its swinging, depend on how high the gripping band is with respect to the center of gravity of the pipe section; and if this height is properly chosen, and the gripping band is made of proper length, the center of gravity is offset just sufficiently from the line through the two pulleys 12 that the pipe may be swung axially to any desired position. This length of the gripping band may be varied as conditions require, by changing the num-

ber of sections 13, thus making the device suitable for pipes of any size. The articulated construction of the gripping band also assists in its gripping action on the pipe.

5 I claim as my invention:

1. In an apparatus for handling concrete pipe sections, the combination of an articulated band arranged to extend part way around the pipe, and a chain the bight of 10 which extends the remainder of the way around such pipe and movably co-operates with the ends of said band to tighten the latter, the ends of said chain extending upward to a lifting device, said band comprising 15 a series of sections removably hinged together so that the length of a band may be varied as required.

2. In an apparatus for handling concrete pipe sections, the combination of a gripping 20 band comprising a series of sections hinged together, the hinge joints being separable

so that the number of sections may be varied, the end members of said band being provided with hooks, and a chain co-operating with said hooks to provide two upwardly 25 extending lifting chain-parts and a chain bight which with said gripping band constitutes a complete encircling device for a concrete pipe section.

3. In an apparatus for handling concrete 30 pipe sections, a gripping band comprising a plurality of sections hinged together with the end sections hook-shaped to co-operate with the chain, the hinge joints being separable so that the number of sections may be 35 varied to vary the length of the band.

In witness whereof I, COLEMAN MERIWETHER, have hereunto set my hand at Louisville, Kentucky, this third day of March, A. D. one thousand nine hundred and 40 twenty-one.

COLEMAN MERIWETHER.
